DESIGN FOR AN INSECT TRAP STAND

Dell D. Spharler, Berkeley, and Forest D. Leader,
Oakland, Calif.

Application November 17, 1941, Serial No. 104,183

Term of patent 14 years

To all whom it may concern:

Be it known that we, Dell D. Spharler and Forest D. Leader, citizens of the United States and residents respectively of Berkeley and Oakland, in the county of Alameda and State of California, have invented a new, original, and ornamental Design for an Insect Trap Stand, of which the following is a specification, reference being had to the accompanying drawing, forming part thereof, wherein:

Figure 1 is a perspective view of the insect

trap stand, showing our design as seen looking down from the top;

Figure 2 is a side elevational view; and

Figure 3 is a perspective view as seen looking up from the bottom thereof.

We claim:

The ornamental design for an insect trap stand, substantially as shown.

DELL D. SPHARLER.
FOREST D. LEADER.
